(57) **CLAIM**

The ornamental design for the water pitcher and filter, as
shown and described.

DESCRIPTION

FIG. 1 is a perspective view of a water pitcher and filter according to a first embodiment of the present design.

FIG. 2 is a top plan view of the first embodiment.

FIG. 3 is a bottom view of the first embodiment.

FIG. 4 is a front view of the first embodiment.

FIG. 5 is a right side view of the first embodiment.

FIG. 6 is a left side view of the first embodiment.

FIG. 7 is a perspective view of a second embodiment of the present design.

FIG. 8 is a top plan view of the second embodiment.

FIG. 9 is a bottom view of the second embodiment.

FIG. 10 is a front view of the second embodiment.

FIG. 11 is a right side view of the second embodiment.

FIG. 12 is a left side view of the second embodiment.

FIG. 13 is a perspective view of a third embodiment of the present design.

FIG. 14 is a top plan view of the third embodiment.

FIG. 15 is a bottom view of the third embodiment.

FIG. 16 is a front view of the third embodiment.

FIG. 17 is a right side view of the third embodiment; and,

FIG. 18 is a left side view of the third embodiment.

The broken line showings are for illustrative purposes only
and form no part of the claimed design.
